UNITED STATES PATENT OFFICE.

THOMAS HAWORTH, OF FALL RIVER, MASSACHUSETTS.

BOBBIN-SMASH PREVENTER FOR WEFT-REPLENISHING LOOMS.

1,381,636.

Specification of Letters Patent. Patented June 14, 1921.

Application filed May 17, 1920. Serial No. 381,956.

To all whom it may concern:

Be it known that I, THOMAS HAWORTH, a subject of Great Britain, residing at Fall River, in the county of Bristol, State of Massachusetts, have invented a certain new and useful Improvement in Bobbin-Smash Preventers for Weft-Replenishing Looms, of which the following is a specification, reference being had therein to the accompanying drawings.

The invention is designed for application to looms of the class in which weft-replenishment is effected automatically through replacement of the spent filling-carrier or bobbin occupying the working shuttle on the lay by a fresh filling-carrier or bobbin transferred to the shuttle from a magazine containing a supply of reserve filling-carriers or bobbins.

20 The general aim of the invention is to provide improved means for preventing "bobbin smashes". The term "bobbin smash" applies to the breakage of warp-threads caused in the flight of a shuttle across a loom, by a filling-carrier or bobbin which projects above the top of the shuttle instead of being completely housed within the latter. Such accidents occur in bobbin-changing weft-replenishing looms as a result of failure of the transferring devices to insert the fresh filling-carrier or bobbin properly into the shuttle at the time of making a transfer, or of a failure of the holding springs of the shuttle to keep the filling-carrier or bobbin 30 in its proper place within the shuttle. The outcome of such failure is that when the shuttle is picked from the shuttle at the replenishing side of the loom toward the other side of the loom, through a shed in the warp-threads, breakage of the warp-threads results from the engagement of the upstanding head therewith.

The invention consists, firstly, in a bobbin-smash preventer for bobbin-changing weft-replenishing looms comprising a shuttle-lock combined with the shuttle-box at the replenishing or magazine side of a loom, adapted to engage a filling-carrier head standing up above the top of the inwardly-moving shuttle, located at such a distance inward beyond the lay-beam opening through which filling-carriers ejected by the replenishing operations descend that the intermediate portion of lay-beam beneath the shuttle will prevent the filling-carrier en-

gaged with the lock from being swung downward through the bottom of the shuttle in consequence of such engagement, and operating to arrest the inwardly-moving shuttle before it has passed into the shed in 60 the warp-threads. By such arrest of the shuttle, injury to the warp-threads is prevented. The described location of the lock avoids liability of the loom to become pick-bound, and thereby guards against tendency 65 to straining or breakage of the parts.

The invention consists, secondly, in the revoluble lock and filling-carrier or bobbin depressor which is described hereinafter.

The features of the invention are illustrated in the drawings, in which latter,—

Figure 1 is a front elevation of portions of the lay of a loom having said features applied thereto, showing also portions of the picker-sticks, the middle portion of the lay 75 being broken out.

Fig. 2 is a partly sectional plan view thereof.

Fig. 3 is a sectional detail on a relatively 80 enlarged scale.

The drawings show portions 1, 1, of a loom lay-beam, a shuttle 8 at the replenishing or magazine side of the loom, and a filling-carrier or bobbin 9 in connection with said shuttle, having thereon a full load 10 85 of weft or filling. 2, 2, are the front-plates of the shuttle-boxes at the two ends of the lay; 3, 3, are the shuttle-box backs, and 4, 4, are the lips projecting forwardly from said backs and constituting the shuttle-box tops; 90 5, 5, are the picker-sticks at the opposite ends of the lay, and 6, 6, are the pickers carried by the said picker-sticks. 7, Fig. 1, is the slot or opening through the lay-beam at the replenishing or magazine side through 95 which spent filling-carriers or bobbins expelled from the shuttle in the performance of the replenishment drop into the usual catcher-box, not shown.

The shuttle 8 is represented in Fig. 2 100 fully home within the shuttle-box at the replenishing or magazine side of the loom, which is the position it occupies at the time replenishment is effected by inserting into the open top of the shuttle-body a filling-carrier or bobbin 9 supplied with a load 10 of weft or filling, and expelling the spent filling-carrier or bobbin through the open bottom of the shuttle-body. In such position of the shuttle, its open bottom is over 110

the lay-beam opening 7 and the latter filling-carrier or bobbin is free to fall through such opening.

The lock a is located adjacent the inner 5 end or mouth of the shuttle-box at the replenishing or magazine side of the loom. In the preferred form of embodiment shown in the drawings it comprises a sleeve a' which is revolubly mounted upon a supporting stud a^2 projecting forward from the back 3 of the said shuttle-box. The said lock is mounted at such a height above the shuttle-race that it just clears the top of the shuttle as the latter slides below it in being 10 picked back and forth across the loom. While the filling-carrier or bobbin carried by the shuttle occupies its proper position within the shuttle, wholly below the top surface of the latter, the movements of the 15 shuttle will not be obstructed by the lock.

If, however, the head of the filling-carrier extends up above the top surface of the shuttle, as in Fig. 1, as sometimes it does following the replenishing operations, the 20 standing head will engage with the lock as in Fig. 1 in the first pick following replenishment, and thereby the shuttle will be arrested in its movement from the replenishing side of the loom toward the opposite 25 side before it has entered the shed in the warp-threads.

To insure stoppage of the shuttle as a 30 result of engagement of the lock with the upwardly projecting head of the filling-carrier or bobbin, I make provision for preventing the lock from expelling the filling-carrier or bobbin from the shuttle or causing 35 it to project below the shuttle. The tendency of such engagement is to cause the 40 barrel and tip of the filling-carrier or bobbin to swing downward through the open bottom of the shuttle. When that happens in practice, it frequently results that the filling-carrier or bobbin is trapped between 45 the eye-end of the chamber within the shuttle-body and the inner end of the opening 50 7 through the lay. This arrests the movement of the shuttle sometimes before the picker-stick and picker have completed their 55 inward picking movement, so that the loom becomes pick-bound, with a tendency to breakage of picker-stick or picking tappet nose. To prevent such action from taking 60 place, I locate the lock at such a distance inward beyond the inner end of the lay-beam opening 7 that the shuttle is allowed 65 to move with the picker far enough to carry its contained filling-carrier or bobbin over the portion of the lay-beam intermediate 70 said inner end and the lock before the engagement takes place. Such portion being beneath the shuttle at the instant when the engagement of the lock with the head takes place, it will prevent the filling-carrier or 75 bobbin from being swung downward so as to

cause it to partly project through the bottom of the shuttle. This location of the shuttle-lock obviates breakage or other injury of the picker-stick and its actuating devices, because the action of the picking 80 tappet in producing the movement of the picker-stick inward ceases before the movement of the shuttle is arrested in consequence of engagement of the head of the filling-carrier with the lock. Usually, when 85 the engagement of the head of the filling-carrier or bobbin with the lock occurs, the shuttle moves relative to the filling-carrier or bobbin until the threader-block or a portion of the wood of the shuttle at the corresponding 90 end of the chamber within the shuttle brings up against the tip of the filling-carrier or bobbin.

The revoluble lock may be made of any 95 approved material, preferably of a character which will not injure the shuttle as a result of contact between the shuttle and the surface of the lock. I contemplate making it of compressed paper stock in roll form, although it may be made of brass or the like 100 composition, or of wood.

An important advantage of a revoluble lock is that it will turn in case the shuttle rises so as to make contact with the surface of the stop; thus I avoid what is known as 105 a "short pick", resulting from friction against the lock, and which would be followed by the loom banging off on the return pick. The lock by revolving operates in improved manner to guide the shuttle properly 110 into the box in case the shuttle should have been thrown too high.

From the foregoing it will appear that by preventing the bobbin from being wholly or partially ejected from the shuttle through 115 the action of the lock, *i. e.*, by compelling the bobbin to remain within the chamber of the shuttle, the lock acts to arrest both the bobbin and the shuttle, and thereby prevents them from entering the shed, while at 120 the same time I safeguard against breakage or injury in the case of the picker-stick and other parts of the picking mechanism.

I contemplate in some cases employing also a revoluble device such as aforesaid, as 125 at a^3 , at the mouth of the shuttle-box at the opposite side of the loom from that at which the magazine is located. In the case of such employment, the device will act as a lock or depressor in connection with an elevated 130 filling-carrier tip.

What is claimed is,—

1. A bobbin-smash preventer for bobbin-changing weft-replenishing looms, comprising a shuttle-lock combined with the shuttle-box at the replenishing or magazine side of a loom and adapted to engage a filling-carrier head standing up above the top of the inwardly-moving shuttle, located at such a distance inward beyond the lay-beam open- 130

ing through which filling-carriers ejected by the replenishing operations descend that the intermediate portion of lay-beam beneath the shuttle will prevent the filling-carrier 5 engaged with the lock from being swung downward through the bottom of the shuttle in consequence of such engagement, and operating to arrest the shuttle before it has passed into the shed in the warp-threads.

10 2. In a weft-replenishing loom, the combination with the lay and a shuttle-box thereon, of a revolute stop and depressor device located adjacent the shuttle-box mouth and adapted to engage a filling-carrier projecting above the top of the shuttle at such 15 a distance inward beyond the lay beam open-

ing through which filling carriers ejected by the replenishing operations descend that the intermediate portion of lay beam beneath the shuttle will prevent a filling car- 20 rier that is positively engaged and held by the stop from being swung downward through the bottom of the shuttle in consequence of such engagement, the said stop adapted to arrest the shuttle before it has 25 passed into the shed in the warp-threads.

In testimony whereof I affix my signature in presence of two witnesses.

THOMAS HAWORTH.
